ENGRAVING AND RELATED MACHINES

George Gorton and Peter M. Henkes, Racine, Wis., assignors, by direct and mesne assignments, to George Gorton Machine Co., Racine, Wis., a corporation of New Jersey

Application December 30, 1932, Serial No. 649,664
Renewed October 7, 1935

26 Claims. (Cl. 90—13.6)

This invention concerns the art of engraving and related machines; and the objects and nature of the invention will be apparent to those skilled in the art in the light of the following explanations of the accompanying drawings that illustrate what we now believe to be the preferred mechanical expression or embodiment of the invention from among other constructions, arrangements and/or combinations within the spirit and scope thereof.

An object of the invention is to so improve machinery for engraving, etching or cutting designs or indicia on work, as to provide a simple, economical and highly advantageous organization capable of successful operation by persons not highly skilled in the operation and control of machinery as heretofore produced for performing such engraving, etching or cutting operations.

20 A further object of the invention is to provide a pantograph engraving machine as an improved self contained portable unit, economical in organization and comparatively simple to understand, operate and control for more or less universal use.

25 A further object of the invention is to provide an improved organization for engraving, etching or cutting designs and/or indicia axially around or partially around as well as longitudinally of the circumference of substantially cylindrical and/or round longitudinally tapered work, and capable of engraving, etching or cutting designs, and indicia on approximately plane or flat surface work, by simple adjustment or substitution of parts.

30 A further object of the invention is to improve various features and combinations to provide an advantageous organization for performing work desired.

40 With the foregoing and other objects in view that will be developed as the description proceeds, the invention consists in certain novel features in structure and organization, and in combinations and sub-combinations as more fully and particularly described and specified hereinafter.

45 Referring to the accompanying drawings, forming a part hereof:

Fig. 1 is a plan view of an embodiment of the 50 invention as an example, the pantograph and parts moved thereby being shown in a central or intermediate position, the copy holder being partially broken away, dotted lines indicating certain hidden parts and the rotative adjustment of the 55 copy holder.

Fig. 2 shows the machine of Fig. 1 in front elevation.

Fig. 3 is an edge elevation from the left hand Fig. 1.

Fig. 4 is a plan view with the pantograph 5 locked in a position forwardly and to the left with respect to Fig. 1.

Fig. 5 is an enlarged vertical sectioned view of the cutter head.

Fig. 6 is a detail elevation of the upper portion 10 of the cutter head showing the bracket carrying the cutter spindle end thrust bearing, swung to abnormal position to permit removal or application of the cutter spindle and its driving pulley or element.

Fig. 7 is a detail vertical section on the line 7—7 Fig. 4.

Fig. 8 is an enlarged detail elevation of the cutter spindle and its driving and depth stop member.

Fig. 9 is an enlarged detail elevation of the 20 form of combined holder and presser foot disclosed by Figs. 2, 3 and 5.

Fig. 10 is an enlarged detail top plan of the 25 holder and foot unit of Fig. 9.

Fig. 11 is a detail end view of the presser foot of Figs. 9 and 10.

Figs. 12 and 13, are enlarged detail side elevation and bottom plan views, respectively, of another form of combined holder and presser foot 30 units.

Figs. 14, 15 and 16 are side elevation bottom plan, and edge elevation views of still another form of combined holder and presser foot unit.

The example of an embodiment of the invention as illustrated by the drawings, provides a horizontal approximately flat strong rigid base 1, that carries the complete organization arranged, in this instance, above its approximately horizontal top side. This supporting frame, for ex- 35 ample, can be composed of a strong rigid casting, the intermediate central top portion of which provides the work table, with the copy holder arranged above and supported from this base, and with a pantograph mechanism arranged and 40 movable above and supported from this base, and in this example carrying the cutter head and its rotary cutter spindle and the motor for driving said spindle, without intending to thereby limit 45 all features of the invention.

50 In the example shown, the pantograph consists of a horizontally disposed and swingable strong main supporting arm 2; a horizontally swingable long arm 3, at its rear end pivotally joined to the free or right hand end of swing arm 2, and ex- 55

tending forwardly therefrom above the base and above the copy holder providing the handle end 3a, and the vertical depending tracer or stylus 4; the horizontal arm or link 5, parallel with arm 3, and pivoted to supporting arm 2, at a point intermediate the length thereof and extending forwardly therefrom above the base and preferably in the same horizontal plane as arm 3; and the front horizontal link 6, parallel with supporting arm 2, and pivotally joining arms 3 and 5, to complete the parallelogram form of pantograph shown in this example, which for simplification in illustration, does not disclose adjustments to vary the reduction scale from copy to 15 reproduction on the work, as the particular reproduction ratio between the copy and reproduction on the work, is not involved in our present invention. For instance, the particular pantograph example as illustrated is set to reduce 20 the copy to about half size in reproducing the same on the work, but our invention is not so limited.

In the example shown, the left hand rear corner portion of the base, with reference to Fig. 25 1, is formed with a strong upstanding bracket 7, usually right angular in cross section and providing an overhanging rigid horizontal top wall or web 7a, a substantial distance above the portion of the base top adjacent the base of bracket 30 7, and said wall 7a, and said portion of the base are provided with longitudinally adjustable screw threaded pintle or trunnion pins 8, that are longitudinally aligned and provided with conical bearing ends, one depending from the wall 7a, 35 and the other projecting up from the base. These two vertical spaced aligned pintles 8, constitute the supporting axis on which the supporting arm 2, is horizontally swingable and by which it is supported. The main arm 2, at its left or 40 fulcrumed end is formed with a vertically elongated strong supporting bearing hub 2a, that provides vertically aligned upper and lower end bearings that receive the cone bearing ends of the normally-fixed pintles or trunnions 8, respectively. These pintles are longitudinally and 45 separately adjustable to take up objectionable looseness in said pivotal supporting connection between said arm and the base. In this example, the main supporting swing arm extends 50 approximately throughout the length of the rear of the base and is horizontally swingable forwardly and rearwardly.

The pantograph arms 3, 5, are spaced apart a 55 distance equal, for instance, to about one half the length of the main arm 2, i. e. from the free end of arm 2, to about the center of the length of said arm although we do not wish to so limit the invention. The arms 3, 5, extend forwardly 60 of the machine from arm 2, and extend thereabove and are strongly supported therefrom against sagging at their forward portions. For instance, the portion of each arm 3, 5, that directly overlies the top edge of arm 2, is formed preferably in one piece with a strong annular vertical hub 9. The arm 2, is provided with strong cylindrical bearing studs 10, rigid therewith and rising vertically from the top edge thereof, one for each hub 9, and extending vertically and centrally therethrough with the hubs 65 mounted on and confined to the studs by radial and end thrust ball or other suitable bearings 11, confining the hubs to the studs, to permit free horizontal swing of the arms 3, 5, on their respective studs 10, and to support said forwardly 70 extending arms in their horizontal position.

The right hand end of front cross link 6, extends over an intermediate portion of the length of long arm 3, and is pivotally joined thereto by a vertical hub 9, centrally receiving a cylindrical stud 10, rigid with and rising from arm 3, and an intervening, preferably, radial and end thrust ball bearing 11.

The front end of pantograph arm 5, and the left hand end of the front cross arm or link 6, of the pantograph, lap one over the other and 10 are pivotally joined to swing on a vertical axis, aligned with the longitudinal axis of the vertical cutter spindle. In fact, the cutter head carried and supported by the pantograph and having a universal lateral or horizontal movement with 15 the pantograph as the stylus thereof traces the copy, is utilized to provide the vertical axis or pivot by which said overlapping ends are pivotally united.

The said overlapping ends of arms 5, 6, are 20 in the form of longitudinally aligned vertical annular hubs 5a, 6a, each rigid with its respective arm, and each axially movable around the common vertical axis. This pivot or axis is formed by the vertical tubular housing or cutter head 25 body 12, which extends centrally and vertically through said two hubs 5a, 6a, from a point below the same to a point above the same, and each hub is independently and rotatively mounted on said body 12, preferably through the medium of 30 concentric radial and end thrust ball bearings 13, which of course hold the two hubs against relative vertical separation and the pivot or axis and said two hubs against relative vertical separation so that the two hubs are coupled together by the axis forming body 12. Below the lower hub 5a, the body 12, is provided with a head or laterally enlarged flange 14, and above the upper hub 6a, the tubular body 12, is provided with a cylindrical portion 15.

The rotary vertical cutter spindle 16, is longitudinally aligned with tubular body 12, and hubs 5a, 6a, and is carried by and movable vertically with and centrally arranged and rotatable in a vertically movable slide or barrel 17, longitudinally aligned with body 12, and longitudinally slidable therein, and extending therethrough from a point below the same to a point above the same. The cutting point 16a, of the spindle depends below the barrel 17, to operate on the 50 work, while the upper end of vertical spindle 16, extends to a point above the barrel and is there provided with a friction belt pulley 18, by which the spindle is driven through the medium of any suitable belt drive from a suitable source of 55 power.

In the example shown, the pulley 18, is driven by a horizontally-arranged single endless friction driving belt 20, from the belt pulley 21, normally fixed on the upper end of the vertical rotary driven shaft 22, of electric motor 23, enclosed in a suitable housing fixed to and carried by the rearwardly projected rear end of pantograph arm 5.

The friction belt 20, is preferably longitudinally 65 elastic or expandable under constant tension to return to its normal length which is less than the distance between the pulleys 18, 21, so that the belt is stretched and under contracting tension when applied to the pulleys in driven and 70 driving relation to maintain the desired belt tightness or driving tension and take up belt stretch. We have with success employed for this purpose an elastic belt composed mainly of rubber or equivalent material, rectangular or ap- 75

proximately V-shaped in cross section, although we do not wish to so limit our invention.

In the organization shown as an example, we gain advantages by mounting the motor as well as the cutter head on the pantograph.

The forwardly extending pantograph arm 5, that aids in upholding and supporting the cutter head located at the front end of said arm, also carries and supports the relatively more or less heavy motor 23, but said motor, in this instance, is located rearwardly beyond the main supporting arm 2, of the pantograph, and is located in and secured to the rigid horizontal forked rear end 5c, of the straight arm 5, that projects rearwardly beyond the main arm 2, to more or less balance the arm 5, and its load on the main arm 2.

The cutter head including its vertical cutter spindle, is supported by the pantograph, in the example shown, above the intermediate or central portion of the base and is universally movable laterally in a horizontal plane above and to all points over said portion of the base, by the pantograph, as the pantograph stylus is moved laterally in a horizontal plane to follow the lines of the copy to be reproduced in scaled relation on the work by the cutter of the spindle included in the cutter head. The pantograph including its load such as the motor, the cutter head, the handle end of the long arm and its stylus, is maintained and supported in an elevated horizontal plane, from the pivotal support of the main swing arm 2, and the remaining arms and/or links of the pantograph including the loads carried thereby, are pivotally supported in elevated horizontal positions and against sagging from said arm 2, while capable of freely swinging laterally in their fixed horizontal planes of movement.

The example shown of an embodiment of our invention, is particularly intended as a small portable machine that can be easily lifted and carried from place to place or transported by hand in an appropriate case, and be operated according to the instructions of a direction sheet, by persons in various walks of life, such as store clerks and others, who are not skilled in engraving machine operation and structure, although of course our invention is not so limited.

We mount any suitable copy holder at the front of the machine in such manner as not to obstruct the horizontal paths of movements of the pantograph and parts carried thereby or the spaces likely to be occupied by the work and work holder above the central area of the base.

For instance, we show a copy holder that embodies a top flat horizontal plate 24, having a flat top surface of sufficient area to receive the flat copy to be reproduced in scaled relation on the work by the cutter. For instance, the copy might consist of a design or indicia such as writing or a signature, drawn or written on a sheet of paper. This sheet of paper will be flattened out on the horizontal top surface of the copy holder plate, and temporarily and stationarily secured thereto by any suitable means, so that the handle end of the long pantograph arm 3, will be free to swing laterally thereover as its vertical stylus traces the lines of the copy. In the example shown, the flat top plate 24, is oblong in form, and is provided with a rigid approximately-cylindrical central vertical depending trunnion or stud 25, removably fitting and rotatable in the vertical bore of an upstanding post 26, rigid or integral with the base and rising from the front right hand corner thereof, whereby the copy holder

plate 24, is held in an elevated horizontal position, and can be clamped or locked by threaded rotatable clamping bolt 27, threaded into a radial tapped hole in post 26, to clamp or release stud 25. When the clamping bolt is rotated to release stud 25, the plate 24, can be rotated on post 26, a quarter turn to present either its long edge or its short edge at the machine front. This rotary adjustment of the plate is limited by spaced lugs 27, rigid with and depending from the plate, contacting a stop 28, rigid with and rising from the base between said lugs 27.

We have discovered the desirability of providing means for temporarily locking the pantograph against horizontal movement, when the machine is not in use, particularly where the invention is embodied in a portable machine adapted to be carried in various positions in a case or otherwise, and particularly where the pantograph is loaded by the cutter head and/or motor, and particularly where the locking means braces the pantograph against sagging under the weight of its load. As an example, we have provided means to lock as well as brace and uphold the main supporting arm 2, from its free end, and also means to lock the long forwardly projecting arm 3 of the pantograph from its front handle end as well as brace and uphold the free end of said arm.

For instance, we provide the free end portion of the pantograph main arm 2, with a vertical socket 2e, opening through its bottom edge, and the base with an upstanding stud 29, having a screw threaded socket open at the upper end of the stud with a rotary threaded bolt 30, threaded into said socket and provided with a handle whereby the bolt can be rotated to withdraw downwardly into the socket from the path of travel of the pantograph arm 2, or in the opposite direction to vertically enter the socket 2e of said arm 2, and bear upwardly against said arm, to lock the arm against horizontal swing and to brace and uphold the arm.

The stylus can be utilized to lock the pantograph through the medium of the pantograph forwardly extending long arm 3, and the copy holder plate. For instance, we show the copy holder plate formed with a vertical socket or hole 31, in its front left hand corner portion to receive the tapered or conical lower end of the stylus and thereby lock the pantograph arm 50 against lateral or horizontal movement. The vertical locking socket 31, is preferably so located with respect to pantograph locking bolt 30, and the range of movement of the pantograph, that when the main arm 2, is locked by bolt 30, the stylus will be, or can be, located in vertical alignment with its locking socket 31. The stylus is normally elevated with its pointed lower end about flush with the top surface of the copy holder plate, but the stylus is preferably screw threaded and meshes with the tapped bore of a vertical hub of the handle end of pantograph arm 3, so that the stylus can be raised and lowered by rotation in said hub. When the arm 2, is to be locked, the stylus by rotation is projected down into socket 31, and to restore the arm 3, for horizontal swing, the stylus is by rotation, elevated to its normal position.

Referring again to the cutter head, the longitudinally tubular and vertically slidable cutter 70 spindle slide or barrel 17, is exteriorly, preferably, cylindrical, and at its upper extremity is formed or provided with an enlarged end or head 17a, having a bore therethrough aligned with the longitudinal bore of the barrel, and internally 75

provided with any suitable bearing 17b, for the relatively rotary longitudinally removable cutter spindle 16.

The lower end of barrel 17, below the cutter head housing, is also provided or formed with an enlarged longitudinally tubular head 17c, as a rigid part of the barrel and providing an interior suitable bearing 17d, for the lower end portion of the longitudinally removable rotary cutter spindle 16.

The cutter spindle 16, is so rotatively and removably mounted in and confined to the barrel 17, as to be carried thereby longitudinally and hence to raise and lower therewith during normal machine operation, and as said barrel is preferably arranged to float on the work during cutting, etching or engraving operations, the barrel is preferably surrounded by a coiled expansion spring 32, within the cutter head housing, compressed between an upwardly facing annular exterior abutment shoulder of the barrel and an upper opposing interior annular shoulder formed by the fixed upper end of said housing 12. This spring 32, constantly acts to yieldingly force the barrel longitudinally and downwardly with its lower end or bottom depth stop presser foot of any suitable construction bearing down against the work.

Means are provided for holding the cutter spindle barrel 17, against axial or rotary movement on its longitudinal axis while permitting free longitudinal sliding movement thereof. For instance, for this purpose, we show an exterior horizontal radially projecting plate or arm 33, rigid with the bottom head 17c, of said barrel, with a rigid straight vertical guide pin 34, fixed to and upstanding from the free end of arm 33, and confined in and slideable longitudinally through the fixed horizontal laterally projecting bottom flange or plate 14, of the cutter head housing. The horizontal arm 33, that is fixed to and moves vertically with said barrel, also serves as a handle or finger hold by which the barrel and its presser foot can be held elevated against the tension of spring 32, whenever such action is desirable or necessary for instance, when work is being applied to or removed from the work holder, etc.

The vertically slideable preferably floating barrel 17, is provided with and carries any suitable bottom pressure foot to bear down on and slidably engage the top surface of the work, and thus limit the downward movement of the barrel with respect to the work and thus constitute a barrel depth stop and consequently a cutter depth stop when the cutter is fed to its limit of downward movement within the barrel with its cutting point projected below the horizontal plane of the presser foot to cutting position to produce cuts in the work of the required depth.

Any suitable means are provided for feeding the cutter spindle longitudinally of its barrel to carry the cutter to and from working depth or position and for holding the same in withdrawn and in cutting positions. For instance, in the example illustrated, we show the barrel 17, provided with an exterior radially projecting pin 35, rigid therewith and located above the cutter head housing and below the enlarged upper end 17a, of the barrel. This pin projects into an inclined or cam slot 36a, in the depending sleeve-like skirt 36, of and rigid with the top head 17a, of the barrel. The head 17a, is longitudinally aligned with the barrel and is arranged above and spaced from the upper end of the barrel and

the cylindrical or sleeve-like skirt of said head slidably and longitudinally receives said barrel in such manner that the head is afforded limited vertical and axial movement on and with respect to the upper end of the barrel, while the barrel and said head are coupled together through the medium of the radial pin 35, and cam slot 36a, to rise and fall as a unit when the barrel is lifted by hand and when depressed by the barrel spring 32, or by gravity. The relative movement of the head 17a, and parts carried thereby, on or with respect to the barrel, is limited by the cam slot 36a, and pin 35, and is caused by rotation of the head on the barrel.

Relative rotation of said head on the barrel in one direction until stopped by engagement of said pin with one end wall of said slot, will raise the head on the barrel and consequently withdraw the cutter spindle from cutting position, while relative rotation of said head in the opposite direction until stopped by the engagement of said barrel pin with the opposite end wall of said slot, will feed the cutter spindle downwardly in the barrel to cutting position. This results because the cutter spindle is virtually carried by and raised and lowered with said upper end head of the barrel.

The head 17a, that carries the cutter spindle, is rotated on its relative movement back and forth with respect to the barrel to feed down and raise the cutter spindle in the barrel, by a rotatable sleeve 37, confined, centered and rotatable on the vertical cylindrical top portion 15, of the cutter head housing, and having a rigid upstanding longitudinally slotted forked arm 37a, in the longitudinal slot or fork of which is confined pin 38, projecting radially from the depending sleeve 36, of the head 17. Rotation of sleeve 37, in one direction on its axis 15, will through the medium of fork 37a, and pin 38, rotate the head 17a, in the same direction on the cutter spindle barrel the limit defined by the cam slot 36a, and pin 35, during which a curved or inclined longitudinal edge wall of said slot will ride on pin 35, to either raise or depress the head 17a, and consequently the cutter spindle with respect to the barrel. Rotation of the sleeve 37, in the opposite direction will rotate head 17a, in the opposite direction to longitudinally move the cutter spindle in the opposite direction from that first noted. The rotation of sleeve 37, is limited by upstanding exterior pin 39, rigid with the bottom plate or flange 14, of the cutter head and located between spaced exterior radial stop lugs 40, rigid with sleeve 37, one of said exterior stop lugs being extended outwardly to form accessible front handle 41, by which the cutter spindle is fed to cutting position and elevated to withdrawn position.

The cutter spindle 16, constitutes a unit spindle and cutter point 16a, in that the spindle and its cutter are in effect integral. The spindle is elongated, cylindrical and of uniform diameter throughout its length except at its usually tapered cutter or cutting point 16a, which can be of the same metal or alloy as the spindle and in one piece therewith, or the cutting point can be formed by a diamond or separate hard metal or other cutting material point permanently socketed and fixed in the tapered lower end of the spindle.

This cutter spindle is of greater length than its barrel 17, and projects above as well as below the same, and suitable means are provided, whereby said spindle and its cutter are removable from and are applicable to the barrel, as a unit, and whereby the cutting depth of the cutter spindle

is set and adjustable with respect to the barrel, and whereby the upward end thrust of the cutter spindle with respect to the barrel is limited, preferably yieldingly and adjustably. For instance, 5 in the example shown, the downward longitudinal movement of the cutter spindle in the barrel 17, is limited by the abutment of the flat level lower end 18a, of the spindle driving pulley 18, with the flat level upper end 17x, of the top head 17a, of 10 the barrel, and hence, in effect, the spindle is supported or upheld in the barrel by the spindle pulley 18, said spindle pulley being normally fixed on the upper end portion of the spindle, whereby 15 the spindle and its pulley are thus handled as a unit, the spindle being applicable to and removable from the barrel bore through the upper end thereof.

To permit predetermining and setting the cutting depth of the spindle with respect to the 20 barrel, the pulley is adjustable longitudinally of the spindle. For instance, we show the pulley formed with a longitudinally split radially contractile spring pulley hub extension 16b. This extension 16b, is longitudinally tapered and exteriorly screw threaded, to receive and mesh 25 with an exterior rotary extension-contracting clamping nut 16c. By rotating the nut to move toward the free end of pulley hub extension 16b, the extension expands and the pulley can be 30 shifted longitudinally of the spindle, and by screwing the nut on the extension toward the pulley, the extension will be contracted on the spindle to fix the pulley to the spindle in the desired position longitudinally thereof to permit 35 the spindle cutter to enter the work a predetermined distance.

This can be accurately predetermined by dropping the cutter spindle into and through the barrel while the barrel is in operative position pressing 40 down on the surface of the work, until the point of the cutter of the spindle rests on the work, the pulley having been first loosened so as to be freely movable on the spindle. A thickness gage piece 45 the thickness of which equals the depth of the cut that the cutter should make in the work, is then placed flat face down on the level flat top end of the barrel top head 17a, that limits the downward movement of the pulley, and then the pulley is slipped down on the spindle whose point 50 rests on the work, until the bottom level face 16a, of the pulley abuts the flat top face of said thickness gage. While thus held, the pulley is tightly clamped in such position on the spindle by the clamping nut 16c, and thereupon, the 55 thickness gage is removed. The cutter spindle is inserted down through the barrel after the feed handle 41, has been moved to its limit to the left, referring to the drawings, to cutter feed or downward limit position.

60 The thrust bearing to receive the upward end thrust of the cutter spindle and to hold the cutter to its work and against objectionable end-wise movement in the barrel, is provided for by a longitudinally threaded screw or bolt 43, arranged 65 above and longitudinally aligned with the spindle and at its lower end having a bearing block or piece 44, fixed thereto and abutting the top end face of the spindle. The bearing block 44, is preferably of such material as to provide an approximately anti-friction thrust bearing for the 70 spindle end. The bolt 43, is supported independently of the cutter spindle, and by screwing the bolt toward or from the cutter spindle end, objectionable longitudinal upward movement of 75 the spindle in the barrel can be eliminated and

the cutter properly held to its predetermined working depth. In the example shown, the end thrust screw 43, is threaded through a tapped vertical hole in the overhanging upper end of a bracket arm 45, and is provided with a jam or locking nut 46. The bracket arm 45, is carried by an exterior rigid radial projection of the top head 17a, of the cutter spindle barrel. This radial projection is formed with a downwardly contracting tapered hole 47, through which the 10 lower end of the bracket arm 45, extends and in which it is rotatable and vertically yieldable. The said end of arm 45, has a tapered portion 45a, fitting and rotatable in the tapered bore 47, which limits the downward movement of the 15 arm. The depending end of arm 45, is screw threaded and carries a nut 48, for securing the arm 45, with a spring washer 49, for yieldingly holding the arm downwardly with its taper 45a, on the tapered seat 47, to maintain a slight tension on bolt 43, downwardly on the cutter spindle, where desirable. By loosening the nut 48, the arm 45, can be rotated on its longitudinal axis to shift the bolt 43, laterally from longitudinal alignment with the cutter spindle and permit removal of the cutter spindle from and its application to the cutter spindle barrel. The arm 45, can, if so desired, be formed with a laterally and downwardly projecting guard finger 50, for the 20 pulley 18, and its driving belt. 25

The lower end of the cutter spindle barrel is provided with a depending presser foot to press down on and slidably engage the top surface of the work in position on or in the work holder for engraving, etching, or cutting by the cutter of 30 said spindle. In the particular example shown, this presser foot is carried by a holder removably fitted on the lower end of the bottom head 17c, rigid with the cutter spindle barrel. For instance, the lower end of head 17c, is externally 35 cylindrical from the plate 33, downwardly and this cylindrical surface 17y, is concentric with the common longitudinal axis of the barrel and its cutter spindle. A fixed radial pin 51, preferably projects from said surface 17y. 40

The barrel presser foot holder consists of a contractile and expansible strong steel sleeve 52, that is longitudinally split with its ends formed by the split spaced apart when the sleeve is in normal contracted form. The length of this 45 sleeve exceeds the length of the cylindrical end 17y, of the barrel head, and said sleeve is adapted to be forced upwardly onto said cylindrical end with the longitudinal space between the split ends registering with pin 51. The sleeve is slipped 50 upwardly on the head until its upper end bears against plate 33, and said sleeve will be tightly yet removably held on the head by the contracting 55 spring tension of the spring metal.

This sleeve 52, is provided with and carries any 60 suitable depressed pressure foot for sliding downward pressing contact with the work surface. Various sleeves 52, can be provided all adapted for removable operative application to the head 17c, of the cutter head as hereinbefore described, 65 and each sleeve is provided with and holds and carries a special presser foot different from those carried by other sleeves 52, and each adapted for use with a particular character of work, so that one sleeve and presser foot can be quickly substituted on head 17c, for another, where the character of the work so requires. For instance, a different or peculiar presser foot may be more desirable than others where cutting, etching or 70 engraving is to be performed circumferentially. 75

and longitudinally of elongated cylindrical work or on elongated round work that is longitudinally tapered throughout or partially throughout its length, and again still a different presser foot formation may be more desirable where the cutting work is to be performed on flat surface work. For instance, we show, one combined or unit presser foot and holder (Figs. 5, 9-11) which consists of a holder sleeve 52, adapted to the head 17c, as before described, provided with and carrying an elongated normally-horizontal thin depressed flat presser foot plate 53, extending diametrically across the holder and having a central hole 54, for the free downward passage of the cutter without contacting the plate. This plate has end flanges 55, perpendicular to the plate and slidably fitting the inner vertical faces of a pair of diametrically opposite ears 56, rigid with and depending from the split sleeve 52, with the plate pivotally mounted from and between said ears on a pair of depressed alined pivot pins 57, radially of the sleeve, and having their axes alined with the central longitudinal or long axis of the plate 53, and depressed approximately into the plane of the flat work-contacting bottom face of plate 53, so that the longitudinal axis of the cutter 16a, will intersect and be perpendicular to said axis on which the plate is transversely rockable. Such a presser foot is of peculiar advantage where elongated cylindrical work or elongated round tapered or partially tapered work is to be operated on, as the elongated presser foot plate 53, having a smooth bottom surface to slidably contact the work, will rest on and extend transversely across the uppermost portion of the longitudinal work surface and can freely slide longitudinally of the stationary work and permit rotation of the work on its longitudinal axis with respect to said plate, while the cutter is depending through the central hole in said plate or foot to full cutting depth.

Where elongated round work that is in whole or in part longitudinally tapered, is held by the roller type of work holder hereinafter described, the just described type of depth stop presser foot having the rocking foot plate 53, is of peculiar advantage in pressing down the tapered work as the foot plate extending transversely across said work automatically tilts or rocks transversely as it moves longitudinally of the tapered work to maintain its bottom surface parallel with the longitudinal inclination of the work with the bottom surface of the plate in contact with the top longitudinal line of the work throughout the transverse center line width of the plate, and this center line width of the plate is intersected by the perpendicular cutter and remains at a fixed level or horizontal plane with respect to the cutter when at working depth, whether the plate 53, is tilted to any degree from the horizontal as well as when said plate is in the horizontal position. The point is that the depth of the cuts made in the work by the cutter will be uniform and the same, when said foot plate is horizontal and following the horizontal top line of the work and when said plate is tilted and following the longitudinally inclined top line of a tapered portion of said work.

The split sleeve spring holder that carries the rockable presser foot plate 53, maintains said plate in position to extend transversely of round or cylindrical work. In the example shown, this is assured by the location of the fixed radial pin 51, of the barrel head 17c, which necessitates the location of the split sleeve presser foot holder, on

said head with the split in the sleeve alined with said pin. As hereinbefore mentioned, the barrel is held against rotation on its longitudinal axis by the upstanding slide post or pin 34.

Another form of depth stop presser foot and holder unit as an example of other forms that can be substituted on the barrel head 17c, in place of the holder and tilttable presser foot unit just described, consists of a split contractile spring material sleeve 52, constituting the holder provided and preferably integral with a depressed bottom stiff presser foot or finger 52a, (Figs. 12, 13) projecting radially and approximately horizontally inwardly with respect to the circle of sleeve 52, with the free end of said finger, preferably, terminating short of the longitudinal axis or center line of said circle or sleeve, along which center line the cutter is located. This depth stop presser foot or finger 52a, is preferably formed at the under side of its free end with a smooth bottom contacting surface or pad 52b, to slidably contact and press down on the work preferably closely adjacent to the cutter to limit the downward movement of the barrel and hence to hold and limit the cutter to its predetermined working depth.

We show still another form of combined depth stop presser foot and holder unit (Figs. 14-16) for application to and removal from the cutter spindle barrel head 17c, and in this last named form, a split contractile spring holder sleeve 52, such as heretofore described, can be employed provided with a fixed depressed elongated presser foot 52d, arranged diametrically with respect to said sleeve with the opposite ends of said foot fixed to diametrically opposite bottom edge portions of the sleeve and with the longitudinal axis of said foot at right angles to the radial plane of the space between the free ends of the sleeve, whereby said foot 52d, will extend transversely across round or cylindrical work as does the swiveled or rockable foot plate 53. The bottom work contacting face of this fixed diametrical foot 52d, provides a central longitudinal depressed line or surface 52e, that is approximately rounded, with opposite faces 52f, diverging upwardly from said center line, in such manner that said bottom surface is approximately of a wide or flat V-shape in cross section for operation on certain classes of cylindrical and slightly longitudinally tapered work, as well as on certain types of approximately flat work.

This foot 52d, is formed with a central vertical hole or opening 52g, for the free passage of the cutting point of the spindle, and the depressed longitudinal work-contacting surface line 52e, is designed to be in the same vertical plane as the vertical axis of opening 52g, and the longitudinal axis of the cutter.

This peculiar work contacting face of diametrical foot 52d, is designed to freely ride or travel upwardly and downwardly on slightly tapered work surfaces and along certain kinds of flat and/or cylindrical surfaces without lifting the cutter from its full set working depth.

We show a roller type of work holder carriage peculiarly adapted for approximately cylindrical work or for elongated approximately round work that is longitudinally tapered throughout its length or throughout a portion of its length, where the design or indicia is to be engraved, cut or etched transversely or circumferentially of the exterior circumference of the work and/or longitudinally thereof and/or spirally around or partially around the same. In this carriage, the

work is arranged approximately horizontally with the longitudinal axis of the work parallel with the front edge of the base, with respect to Fig. 1, of the drawings, or transversely with respect to 5 the front to rear center line of the machine shown.

The cutter head is so operatively coupled to the work holder carriage that the carriage and work will remain at rest and the depth stop 10 presser foot of the cutter spindle barrel will slide longitudinally of the work when the cutter head is moved in a straight line direction longitudinally of the work, and in such manner that the carriage will be moved forwardly and/or rearwardly 15 with the cutter head to rotate the work on its longitudinal axis with respect to the cutter head and its cutter and presser foot when the cutter head is moved in a straight line direction transversely with respect to the longitudinal axis 20 of the work, and so that movements of the cutter head on inclined or oblique lines with respect to said transverse and longitudinal lines of cutter head movement with respect to the longitudinal axis of the work, will be properly translated into 25 movements of the work holder carriage and rotation of the work and movements of the cutter head longitudinally of the work and with respect thereto.

For instance, as an example, we show the approximately central intermediate top area of the base over which the perpendicular cutter head is universally movable in a horizontal plane, formed with rigid elevated straight spaced tracks that provide more or less wide flat horizontal 30 top preferably friction surfaces 59. Between said tracks, we show a fixed straight horizontal guide rail 60, parallel with said tracks and their top surfaces 59. These straight-line tracks and rail extend rearwardly in the particular example 35 illustrated, and a work holder carriage is mounted thereon and confined thereto to straight-line forward and rearward travel. This carriage consists of an open horizontal annular or horizontal loop-like frame 61, having a central rigid front 40 to rear depending guide rail 62, straddling and slidably longitudinally of the fixed rail 60, to confine the carriage accurately to its straight line 45 travel forwardly and rearwardly. The carriage is supported by a pair of elongated spaced parallel horizontal cylindrical rollers 63, rotatively 50 mounted in the opposite side bars of the carriage frame 61, on axes that are perpendicular to the straight line path of travel of the carriage. These rollers rest and roll on the flat track surfaces 55 59, and extend transversely across said track surfaces. The rollers preferably are formed or provided with more or less resilient friction surfaces that will frictionally engage the surfaces 59 without slip and that will frictionally 60 engage and hold the surfaces of the work without slip. We find rubber surfaced rolls satisfactory for the purpose, where the rubber or its substitute or equivalent is more or less resilient, but do not wish to so limit our invention. The 65 diameter of the two similar rolls is such that the rolls extend below the carriage frame to uphold said frame above surfaces 59, and are exposed above the frame to permit the elongated round work W, to be placed from above the carriage 70 longitudinally in the work holding trough formed by the upper adjoining sides of the rolls so that the longitudinal axis of the work will be parallel with the axes of the two rollers.

When the carriage is propelled along the 75 tracks, its rolling support, namely, the two roll-

ers travel on said tracks and are both thereby rotated in the same direction but the surfaces of the upper adjacent portions of the two rollers that support and contact the work travel uniformly in opposite directions and consequently 5 rotate the work on its longitudinal axis with the top surface of the work traveling in the opposite direction to that of the work carriage and cutter head, and with the transverse travel of the surface of the work equal to the distance of the 10 forward or rearward travel of the cutter (cutter head) transversely with respect to the longitudinal axis of the work.

The cutter head is operatively coupled to the roller work carriage by a forwardly extending 15 rigid arm 65, at its rear end carrying a normally-fixed vertical elongated plate 66, having a longitudinally grooved bottom edge 66a, parallel with the axes of the rollers and fitting down on and straddling a long straight rigid upstanding edge 20 67, fixed to the rear end of the frame 61, of the carriage and parallel with the axes of said rollers.

When the cutter head is moved forwardly or rearwardly the carriage is pulled forwardly or pushed rearwardly the same distance by the 25 plate 66, that straddles the long edge 67, fixed to the carriage. When the cutter moves in a direction longitudinally of the rollers and work, the plate 66, slides freely longitudinally of and on the carriage edge 67, the carriage and work 30 remaining at rest.

The arm 65, forms a fixed rearward extension of the bottom head or plate 14, of the cutter head, and the depending plate 66, is preferably normally fixedly clamped to the rear end of 35 arm 65, by one or more bolts 68, so that the plate 66, can be removed, when it is desired to remove the roller work carriage, as when it is desired to operate on flat or other work clamped down on the rails 59, by any suitable means. 40

When the plate 66, is in operative position secured to arm 65, and slidably interlocking with carriage edge 67, the cutter head is thereby held against turning or rotating on its vertical longitudinal axis and the arm 65, is held in its rearwardly projecting position parallel with the straight line path of work holder roller carriage movement. 45

The coupling such as arm 65, plate 66, and straight edge 67, between the cutter head and 50 work holder carriage, also maintains the proper operative position of the cutter and cutter spindle barrel directly above the work holding trough with the vertical axis of the cutter located in a vertical plane parallel with and midway between 55 the longitudinal axes of the two rollers, so that the vertical axis of the cutter will be maintained in the vertical plane in which the longitudinal axis of the work is located whatever may be the location of the cutter longitudinally along the 60 work, and this is true whatever may be the diameter of the round elongated work within the capacity of the particular machine and its work holding rollers.

In operation, when the desired copy has been 65 secured in flat position on the copy holder, so that the design or other indicia can be traced by the stylus and is properly arranged with respect to the length of the work in the rollers of the work carriage, the spindle barrel is lifted 70 by the fingers and the elongated work is placed from the top in the trough formed by the rollers, and below the presser foot of the elevated barrel, the stylus, cutter head and carriage having been shifted to place the stylus at the beginning of 75

the copy to be traced and to place the portion of the work where the production thereon is to begin, directly below the elevated presser foot. The barrel is then allowed to descend on the work with its depth limiting presser bearing down thereon under more or less pressure to hold the work into the desired non-slip frictional engagement with the two rollers and to hold the peripheries of the rollers down into frictional non-slip engagement with the track surfaces 59. The operation of the belt drive of the cutter spindle can then be started and the lever 40, swung to its limit to feed the cutter down through the presser foot to its full cutting depth, and the 10 engraving, cutting or etching operation can then proceed to reproduce the copy in scaled relation on the work. When the reproduction has been completed on the work, the cutter is elevated by swinging back lever 40, etc. and the spindle barrel 15 is raised by hand, to release the finished work for removal from the rollers.

As hereinbefore mentioned, the work holder roller carriage 61, 63, is separable from the cutter head and removable from tracks 59, and the machine base, in the event that work not adapted to said carriage, is to be operated on by the cutter. In such event, the cutter head and carriage 61—63, are shifted by the pantograph to such abnormal position to the rear and left, that 20 the plate 66, will slide endwise from the left hand end of carriage straight edge 67, thus freeing the carriage so that it can be removed from the machine, and thereupon plate 66, is removed from arm 65. This same result can be accomplished 25 by so forming plate 66, and its mounting, as to permit release and removal thereof from arm 65, and from carriage straight edge 67, leaving the work holder carriage released for removal from the machine. The cutter head is then locked 30 against independent turning or rotation on its longitudinal axis, by rotation of the radial rotary stop screw 70, in the direction necessary to carry its end into locking engagement with the exterior radial notch 71, in the hub 5a, of the 35 pantograph lever 5. The screw 70, is carried by the bottom head 14, of the cutter spindle barrel. This head 14, for this purpose, is formed with a central forwardly projecting arm upturned at 40 its front end and provided with a tapped radial hole alined with notch 71, and the screw extends through and meshes with the thread of this hole. This screw is withdrawn outwardly from 45 said notch, as shown, when the work holding roller carriage is operatively arranged in the machine and coupled to the cutter head to thereby hold said head against relative axial movement.

When the carriage has been removed and the cutter head has been thus locked to pantograph 50 arm 5, and an appropriate cutter depth presser foot and holder unit, has been placed on the cylindrical lower end of the bottom head of the spindle barrel, the machine, after proper adjusting, is ready for operation on the flat or the like 55 surface of work which can be secured on the track surfaces 59, or on a plate or bed resting on said surfaces, by suitable removable clamp pieces at their inner ends bearing down on the work and at their outer ends bearing on the top 60 surface of the base, and drawn and held down in clamping relation to the work by upstanding removable clamping screws or bolts entering tapped holes in the base with the bolt heads bearing down on the clamps at points intermediate 65 their lengths, as will be understood by those

skilled in the art, without illustration by the accompanying drawings.

The term "engraving machine" is employed herein in a generic sense to include all apparatus to which our invention can be or is adapted 5 for marking, etching, engraving or otherwise cutting work according to and within the scope of our invention. While we have herein specifically described and disclosed in detail an embodiment of the invention as an example from 10 among others, yet this disclosure has not been made for purposes of limitation except where required by the prior art, as it is our desire and intention to cover all generic and specific features of our invention as broadly and fully as it 15 is legally possible.

What we claim is:—

1. An engraving machine including a cutter head having a rotary cutter spindle, said head movable laterally while its cutter spindle is operating on the work; a motor for driving said spindle; and a horizontally arranged pantograph supporting and carrying said cutter head and said motor, and embodying pivotally connected laterally swingable pantograph arms one of 25 which constitutes the pantograph supporting main arm provided with and swingable on a vertical axis that supports the pantograph and its load, said motor being arranged with respect to said main arm to exert a counterbalancing influence on other pantograph arms loaded by said 30 cutter head.

2. An engraving machine embodying a horizontally disposed and movable pantograph of the jointed horizontally swingable arm type; and a 35 cutter head having a vertical cutter spindle, said cutter head included in and supported and carried laterally by said pantograph, said head providing the vertical axis joining a pair of the 40 pantograph arms.

3. An engraving machine embodying a laterally swingable pantograph of the swingable pivotally connected arm type including a main supporting arm pivotally supported from one end, arms pivotally supported by and extending laterally from said main arm, and a cross arm pivotally supported from and joining said laterally extending arms; and a vertical rotary cutter spindle mounted in and supported and carried laterally by said pantograph and alined with the 50 common vertical axis on which said cross arm and a laterally extending arm are joined and swingable.

4. In an engraving machine, in combination; a horizontally disposed laterally swingable pantograph of jointed pantograph arms; a vertical depending rotary cutter spindle supported, upheld and carried laterally by said pantograph and extending through at least one of said arms; and a 55 motor mounted on an arm of said pantograph and held thereby spaced laterally from said spindle and constantly maintained in driving relation to said spindle.

5. In combination; a base having an upstanding bracket with an elevated rigid overhanging portion; a horizontally disposed pantograph elevated over said base and including a main pantograph supporting arm supported from the base and said bracket to swing on a vertical pantograph supporting axis, said pantograph including 70 spaced lateral swing arms pivotally supported from said main arm, and a cross arm pivotally supported from said lateral arms; a depending vertical rotary cutter spindle upheld and carried laterally by said pantograph; and a motor up- 75

held by and mounted on said pantograph for driving said spindle, said motor being spaced laterally from said spindle and maintained in driving relation thereto, said pantograph supporting said motor beyond one side of said main arm and said spindle beyond the opposite side of said main arm.

6. In combination, a base adapted to carry the work; a horizontally disposed copy holder supported by said base; a horizontally disposed pantograph arranged above said base and including a rear horizontally disposed forwardly and rearwardly swingable main supporting arm at one end supported from said base by a vertical pantograph-supporting axis, a long arm pivotally supported from the free end of said main arm on a vertical axis and extending forwardly over said copy holder and provided with a vertical copy tracing stylus; a second swing arm extending forwardly from an intermediate portion of the length of said main arm and pivotally supported therefrom on a vertical axis, and a front cross arm pivotally joining said long and said second forwardly extending arms on vertical axes; a cutter spindle driving motor mounted on and carried by a pantograph arm beyond said main arm; and a depending vertical rotary cutter spindle mounted in and carried laterally by said pantograph.

7. In an engraving machine, in combination; a base; a pantograph elevated and movable thereover and pivotally supported therefrom; and manually-actuated normally-retracted locking means, adapted to be projected to operative positions locking the pantograph with respect to the base against relative movement.

8. An engraving machine embodying a pantograph including pivotally joined laterally swingable pantograph arms; a cutter head carried by said pantograph and providing a longitudinally tubular axis on which a pair of said arms are swingable; a longitudinally tubular vertical cutter spindle barrel in said axis and provided with a bottom depth stop presser foot for pressing down on the work; and an elongated rotary cutter and spindle unit extending longitudinally through said barrel to project its cutter below the level of said foot.

9. In an engraving machine, a cutter head provided with a cutter spindle barrel having a longitudinal bore and internal cutter spindle bearings, said barrel having a bottom head; a combined depth stop presser foot and its holder mounted on said bottom head and removable therefrom and applicable thereto as a unit; and a removable cutter spindle mounted in said barrel bore.

10. In an engraving machine, a cutter head provided with a rotary cutter spindle barrel and its rotary cutter spindle and depth stop means determining the cutting depth of the cutter, said barrel at its lower end provided with a depth stop pressure foot and its holder as a unit, said unit consisting of a contractile sleeve longitudinally removable from and applicable to the lower end of said barrel, and a depth stop presser foot to press down on the work adjacent to the cutter, and carried by and constituting a permanent part of said unit.

11. In an engraving machine, a cutter head, a longitudinally movable barrel in said head; an elongated rotary spindle provided with driving means and a cutting point, said spindle mounted in said barrel and longitudinally removable therefrom, and means to raise and lower the spindle to feed and retract the same in said barrel em-

bodying a rotary sleeve centered on the barrel and operatively coupled to said spindle by means including a pin and cam slot.

12. In an engraving machine, a base having an upstanding post with an open-top socket, and an upstanding stop remote from said post; a horizontal copy holder plate having a rigid depending trunnion rotatably fitted in said socket, said post having means for clamping and releasing said trunnion, therein; said copy holder plate having spaced depending rigid stop lugs, said stop of the base being located between said stop lugs and in the path of movement thereof; a laterally movable pantograph having an arm extending above said plate and provided with a depending stylus; and a cutter head universally movable laterally by said pantograph.

13. In engraving and related machinery, a barrel for the rotary cutter spindle, and a removable combined holder and depth stop presser foot for said barrel embodying a holder sleeve and a transversely arranged depressed presser foot carried by said sleeve.

14. A barrel and a vertical cutter carried thereby in combination with a depth stop presser foot for said barrel including a plate having a central vertical opening for the free passage of the cutter, said plate having a flat bottom surface to slidably engage the work, said plate being rockable on a transverse axis located in the plane of said bottom surface and at right angles to and intersecting the longitudinal axis of the cutter at right angles.

15. A cutter spindle barrel, in combination with a combined holder and presser foot unit adapted to said barrel and including a horizontally disposed diametrical presser foot fixed to said holder and having a vertical opening for the free passage of the cutter and a bottom surface with a depressed work-contacting intermediate face and opposite diverging faces.

16. In engraving and related machinery, an elongated cylindrical rotary spindle at one end providing a cutting point, and a removable concentric driving member for said spindle, having a contractile hub extension and its clamping and releasing means.

17. In engraving and related machinery, a cutter head, and an elongated cylindrical spindle provided with a cutting point, said spindle provided with a driving pulley normally fixed thereto and adjustable longitudinally thereof to vary the cutting depth of said point, said spindle being longitudinally applicable to and removable from said head and being supported and suspended in said head by and from said pulley.

18. A cutter head having a vertically movable cutter spindle barrel including a top head having a limited vertical movement with respect to said barrel for feeding the cutter spindle in the barrel to and from withdrawn and cutting positions; a cutter spindle mounted in and extending longitudinally through said top head and the barrel and longitudinally removable upwardly therefrom and applicable downwardly thereinto and provided with means whereby the cutting depth of the spindle can be determined; means providing an end thrust bearing for the top end of the spindle above said top head, said means being movable to free said spindle for removal from the barrel and said top head, said means moving vertically with said top head; and means applied to said top head for raising and lowering the same with respect to said barrel and for holding the same in the position to which moved.

19. A reproducing machine including a laterally swingable jointed pantograph embodying a swingable arm; a cutter head having a vertical longitudinal axis and provided with an axial 5 spindle for the work cutter, said head being mounted on and carried by the pantograph; means establishing a bearing between said cutter head and said arm for relative axial movement between said head and said arm on an axis 10 alined with said longitudinal axis of said head during operative lateral movements of the pantograph; and means for locking said head and arm against said relative movements on said axis and for freeing said head and arm for said relative axial movements.
20. A reproducing machine including a laterally swingable pantograph embodying pivotally joined arms; a cutter head provided with and carrying a longitudinal vertical spindle for the 15 work cutter, said head being mounted on and carried by the pantograph; means establishing alined bearings between said head and two of said pantograph arms for relative axial movements between the head and said arms on an axis longitudinally of said head; and means for locking said head and one of said arms together against said relative axial movement and for releasing said head from said arm to permit said relative movements.
21. A depth stop unit for a cutter slide barrel, embodying a sleeve adapted to longitudinally and tightly embrace the barrel end against relative longitudinal normal movements thereon, said contractile sleeve being longitudinally removable 30 from and applicable to said barrel end; and a transversely arranged presser foot forming a part of said sleeve and arranged transversely and inwardly thereof depressed below the center opening of the sleeve and the barrel end, to engage and press down on the work surface.
22. In combination; a base to carry the work; a horizontally disposed copy holder; a horizontally disposed parallelogram pantograph arranged 35 over said base and embodying a laterally swingable main arm supported from said base on a pantograph-supporting vertical axis, a long swing arm extending laterally from and mounted to said main arm on a vertical axis and movable over said copy holder and adapted to be provided 40 with a tracing stylus, a second swing arm extending laterally from said main arm and mounted thereto on a vertical axis, and a cross arm spaced laterally from said main arm and pivotally mounted from said two swing arms on 45 vertical axes; a cutter head supported by and carried laterally over the work by said pantograph and provided with a vertical rotary cutter spindle; and a cutter-spindle-driving motor maintained and supported by said pantograph in 50 normal spindle driving association with said cutter head, said pantograph supporting said motor from and laterally beyond said main arm, and maintaining and supporting said cutter head laterally beyond the opposite side of said main arm from said motor.
23. In combination with a pantograph including a fixed point and linkage mechanism extending therefrom carrying a tracing point for moving over a flat outline and a second tracing point for making the desired copy on the work, a work 5 support, a carriage on which said work support is rotatably mounted, means for positively connecting said pantograph and said carriage for movement of the latter in a direction transversely of the axis of said rotatable work support, and 10 means between said carriage and said support to rotate the latter upon transverse movement of the former for continuous alignment of the axes of said support and said second tracing point.
24. In combination with a pantograph includ- 15 ing a fixed point and linkage mechanism extending therefrom carrying a tracing point for moving over a flat outline and an engraving tool for cutting the desired copy on the work, a work support, a carriage on which said work support 20 is rotatably mounted, means for positively connecting said pantograph and said carriage for movement of the latter in a direction transversely of the axis of said rotatable work support, and means between said carriage and said support to 25 rotate the latter upon transverse movement of the former for continuous alignment of the axes of the work and said engraving tool.
25. In combination with a pantograph includ- 30 ing a fixed point and linkage mechanism extending therefrom carrying a tracing point for moving over a flat outline and an engraving tool for cutting the desired copy on the work, a carriage providing a work support for rotating the work on its longitudinal axis, an operative connection 35 between said pantograph and said carriage for movement of the latter in a direction transversely of said axis of the work, and means for causing rotation of said work support and the work upon said transverse movement of said carriage for continuous alignment of the axes of 40 the work and the engraving tool.
26. In combination with a pantograph includ- 45 ing a fixed point and linkage mechanism extending therefrom carrying a tracing point for moving over a flat outline and an engraving tool for cutting the desired copy on the work; a work supporting and rotating holder movable in either direction along a straight line path, means being provided actuated by said straight line movements of said holder whereby the work is rotated while supported and carried by said holder; and an operative connection between said pantograph and said work holder for actuating said work holder on its said straight line movements by 55 lateral movements of said pantograph in directions longitudinally with respect to said path of movements of the work holder, said connection being free to permit movements of said pantograph transversely with respect to said path of work holder movements, independently of said work holder to carry said engraving tool longitudinally of the then stationary work.

GEORGE GORTON.
PETER M. HENKES.
